(57) **CLAIM**

The ornamental design for a status indicator panel as shown and described.

DESCRIPTION

FIG. 1 is a front, left-side, top perspective view of a status indicator panel, showing the new design;

FIG. 2 is a front elevational view thereof;

FIG. 3 is a rear elevational view thereof;

FIG. 4 is a left-side elevational view thereof, the right side elevational view (not provided) being a mirror image thereof; and,

FIG. 5 is a top plan view thereof.

The broken lines depict parts of the status indicator panel that form no part of the claimed design. The dot-dash chain lines depict boundaries of the claimed subject matter and form no part of the claimed design.
